FIRE-CONTROL MEANS FOR SEMI-AUTOMATIC FIREARMS

Thomas R. Robinson, Jr., Newtown, Conn., assignor to The Marlin Firearms Company, New Haven, Conn., a corporation of Connecticut

Application November 15, 1947, Serial No. 786,232

9 Claims. (Cl. 89—145)

1

The present invention relates in general to firearms and more especially to a self-loading firearm of the type disclosed in my co-pending application Serial No. 766,663 filed August 6, 1947, now Patent No. 2,454,885, issued November 30, 1948.

An object of the present invention is to provide superior fire-control means for firearms of the type wherein the energy of explosion of a cartridge is used to perform the operations incident to reloading the firearm in preparation for the next shot.

A further object of the invention is to provide a self-loading firearm with superior fire-control means wherein positive means is provided to prevent more than one shot from being fired each time the trigger is pulled.

A still further object of the invention is to provide a self-loading firearm with superior anti-doubling means embodying a minimum number of elements, all of which are extremely economical to manufacture, easy to fabricate and durable in use.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a broken side elevation in section of a self-loading firearm embodying the improved anti-doubling means of this invention, the breech-bolt of the firearm being shown in its closed position and the firing-plunger held in its retracted cocked position by the sear;

Fig. 2 is a fragmentary plan view on section line 2—2 of Fig. 1 showing the position of the disconnector of the anti-doubling means at the time the breech-bolt is in its forward breech-closing position;

Fig. 3 is a fragmentary plan view similar to Fig. 2 but showing the disconnector of the anti-doubling means displaced by the camming action of the rear end of the breech-bolt as the latter moves out of battery;

Fig. 4 is a fragmentary end elevation of the receiver of the firearm on section line 4—4 of Fig. 1 showing the disconnector of the anti-doubling means immediately above the transmitting-member thereof and in contact with the sear;

Fig. 5 is a fragmentary end elevation of the receiver of the firearm similar to Fig. 4 but with the disconnector of the anti-doubling means

2

shifted to the left out of alignment with the transmitting-means;

Fig. 6 is a fragmentary end elevation of the receiver of the firearm on section line 6—6 of Fig. 1 showing the relationship between the safety and the transmitting-member of the anti-doubling means;

Fig. 7 is a plan view of the underside of the breech-bolt showing the cam-slot therein;

Fig. 8 is a perspective view of the disconnector of the anti-doubling means of this invention; and

Fig. 9 is a perspective view of the transmitting-member of the anti-doubling means of this invention.

Referring particularly to Fig. 1, the firearm chosen for the purposes of illustrating the present invention embodies a substantially solid stock indicated generally at 10 having a longitudinal recess 11 substantially rectangular in cross section formed in the top side of the stock to accommodate the barrel, receiver and trigger-plate assembly of the firearm. A trigger-guard 12 is secured to the underside of the stock opposite a vertical aperture which communicates with the stock-recess 11 adjacent the rear end wall thereof for accommodating the finger-piece 14 of the trigger.

The receiver indicated generally at 15 comprises a substantially-cylindrical member preferably formed from a suitable length of tubular steel stock open at its opposite ends. The interior of the receiver constitutes a cylindrical chamber 16 for the action or breech-bolt 17 of the firearm; and a cylindrical sleeve-portion 18 rearwardly of the chamber 16 in which is secured the end-closure or receiver-plug 19. The barrel 13 is threaded or otherwise fixedly secured in the forward end of the receiver. As indicated clearly in Fig. 1, in this type of firearm the action-chamber 16 comprises a rear section 20 and a forward section 21, the latter being of relatively small internal diameter and formed by securing a substantially-cylindrical bushing 22 of relatively-thick wall section in the forward open end of the receiver. The breech-bolt 17 is likewise formed of two sections of different diameters corresponding to the size and shape of the respective cylindrical sections 20 and 21 of the chamber 16, the forward reduced end 23 of the breech-bolt having a spring-retracted firing-pin 24 supported for longitudinal movement therein. The rear-end portion 25 of the breech-bolt is provided with an axial aperture 26 which gives access to the rear end of the firing-pin and which also chambers the forward end of the action-spring 27 and the for-

wardly-projecting end of the firing-plunger 28 and firing-plunger spring 29. The firing-plunger is adapted to be held in its retracted cocked position, as shown in Fig. 1, against the force of the compressed spring 29 by a sear 30 which is pivotally mounted on a transverse pivot-pin 31 in a longitudinal groove formed in the underside of the receiver-plug 19 and is biased by a sear-spring 32 normally to engage its nose 33 against a shoulder 34 of the firing-plunger 28 to hold the latter in its cocked position. By withdrawing the nose 33 of the sear out of engagement with the shoulder 34 of the firing-plunger, the latter will be released and thrust forwardly by the force of the compressed spring 29 into engagement with the rear end of the firing-pin 24.

For a more detailed description of the firing-plunger and end-plug assembly, reference may be made to my copending application Serial No. 788,529, filed November 28, 1947. The underside of the receiver is provided with a substantially-rectangular metal frame, hereinafter referred to as the trigger-plate 35, in which is mounted the elements of the fire-control means and the anti-doubling mechanism which forms the subject of the present invention.

The trigger of the firearm is indicated generally by the number 36 and is pivotally supported in the rear end-portion of the stock-recess 11 by a substantially-U-shaped bracket 37, the bottom of which is secured to the bottom of the stock-recess by a pair of screws and is slotted longitudinally to accommodate the finger-piece 14 of the trigger. The finger-piece constitutes a substantially-solid piece, the upper end of which is welded or similarly secured between inturned flanges 38 formed on the bottom edges of a pair of spaced parallel sheet-metal trigger-arms 39, the forward ends of which are pivotally secured by pivot-pins 40 in juxtaposition to the corresponding inner walls of the bracket 37 and adjacent the upper edges thereof. The rearwardly-extending ends 41 of the trigger-arms 39 project upwardly at substantially right angles to the arms and are joined at their upper ends by a common integral transverse bridge-member 42. The latter is provided with a blister 43 extending longitudinally thereof for building rigidity into the structure and for providing substantially line contact with the transmitting-member of the anti-doubling means, as hereinafter described.

The term "anti-doubling" as used herein and in the appended claims is a well-known expression in the art for denoting the functional characteristics of mechanism of a self-loading firearm for positively preventing more than one shot from being fired with a single pull of the trigger. In general, the anti-doubling means of the present invention comprises two principal elements, namely, a transmitting-member indicated generally at 44 and a resilient disconnector indicated generally at 45, the transmitting-member being adapted to transmit the motion of the trigger to the disconnector and the latter, in turn, being adapted by flexure to transmit a lifting motion to the sear to disengage the nose 33 of the latter from the shoulder 34 of the firing-plunger, but only when the breech-bolt is in battery, that is to say, in breech-closing position.

Referring more especially to Figs. 1 and 9, the transmitting-member 44 may be fabricated from solid stock, but preferably is formed from stiff sheet metal for greater economy, and comprises an elongated substantially-rectangular member having a top-plate 46 and two depending side

walls 47 at substantially right angles thereto, the forward ends of which are provided with axially-aligned transverse apertures 48. An inturned flange 49 is provided on the lower edge of each side wall adjacent its rear end and at substantially right angles thereto to form transverse bearing-surfaces adapted to be engaged by the aforesaid transverse bridge-member 42 of the trigger. Immediately forwardly of the inturned flanges 49 of each side wall 47 is a clearance-recess 50 formed in the lower edge of each side wall for accommodating the transverse pivot-pin 51 of the manually-operated safety indicated generally at 52 and described in detail below.

15 The top-plate 46 of the transmitting-member is provided adjacent its rear end with a longitudinal axially-aligned substantially-rectangular slot 53 for accommodating an element of the safety, as hereinafter described; and immediately forwardly of the slot 53 is a substantially-square slot 54 which is offset laterally from the longitudinal axis of the top-plate 46 such that its longitudinal inner edge is substantially in axial alignment with the longitudinal axis of the top-plate. Formed integrally on the inner edge of the square slot 54, preferably by bending up a sheet metal tongue produced in stamping out the slot 54, is an upwardly-projecting lifting-lug 55. The latter is made substantially-L-shaped in cross section, as shown especially well in Fig. 9, so as to provide a flat beveled surface 56 which extends transversely to the right of the inner edge of the slot 54 and makes a slight angle vertically to the horizontal plane of the top-plate 46 of the transmitting-member. In the present embodiment, the aforementioned vertical angle of the beveled surface 56 is of the order of three degrees. As indicated clearly in Fig. 1, the lifting-lug 55 is substantially intermediate the opposite ends of 20 the transmitting-member. Forwardly of the lifting-lug and between it and the front end of the transmitting-member is an integral leaf-spring 57 which comprises a truncated-shaped strip of metal stamped from the top-plate 46 and bent upwardly therefrom about its base, the forward end of the leaf-spring being elevated above the horizontal plane of the top-plate and bent over slightly to provide a convex bearing-surface 58. Although the lifting-lug 55 and the leaf-spring 57 are, for economical reasons, formed from bent-up stock of the transmitting-member, it will be appreciated that these elements may be formed separately and secured to the top-plate of the transmitting-member in any suitable manner. 25 The forward edge of the top-plate 46 is provided with a concave recess to allow clearance for the pivot-post of the disconnector in assembling the latter in the receiver of the firearm, as described below.

30 The transmitting-member 44 is adapted to be pivotally mounted in the trigger-plate 35 by passing a pivot-pin 59 through the transverse axially-aligned apertures 48 in the side walls 47 of the transmitting-member and corresponding apertures in the side walls of the trigger-plate. The transmitting-member is supported thus for pivotal movement in the vertical plane of the trigger-plate, the rear end of the transmitting-member being free and adapted to extend over 35 the bridge-member 42 of the trigger and to be supported thereon by engagement of its inturned flanges 49 with the blister 43 thereof. Moreover, the rear end of the transmitting-member is held down resiliently in contact with the latter by the force of the leaf-spring 57 which is under slight

compression due to engagement of its bearing-surface 58 against the underside of the receiver. As a further consequence of this construction, the leaf-spring also constitutes resilient means for holding the trigger 36 in its normal forward position and for returning the trigger to its normal position after having been retracted for discharging the firearm. As stated above, the rear end of the transmitting-member is normally supported by the bridge-element of the trigger, but if in disassembling the firearm or for any other reason the trigger should be removed, then the rear end of the transmitting-member would drop down and be supported on the transverse pivot-pin 51 of the safety by engagement of the bottom edges of the clearance-recesses 50 therewith.

The safety comprises the aforesaid pivot-pin 51 which is pivotally supported at its opposite ends in transverse axially-aligned apertures in the depending walls of the trigger-plate 35 and provided with a flat 60 extending from substantially the middle thereof to its right-hand end, as seen clearly in Fig. 6. This end of the pivot-pin is reduced in diameter to provide a trunnion 61 and a substantially-square shoulder 62, the latter being adapted to abut against the inner face of the corresponding wall of the trigger-plate to prevent transverse movement of the pivot-pin to the right, as seen in Fig. 6. The opposite or left-hand end of the pivot-pin 51 extends through the corresponding wall of the trigger-plate and has a manually-operated handle 63 secured thereto for rotating the pin. Mounted by a sliding fit on the flattened portion 60 of the pin 51 and abutting against a shoulder 64 formed by the flat is a safety-arm 65 having an apertured hub 66, the aperture of which is formed with a transverse cord adapted to cooperate with the flat 60 of the pivot-pin 51 to lock the arm against rotation thereon. A cotter pin 67 or the like is inserted in a diametrical aperture of the pivot-pin in juxtaposition to the right-hand face of the safety-arm to secure the latter from moving transversely thereon. Mounted on the left-hand end of the pivot-pin 51 between the corresponding wall of the trigger-plate and the left-hand face of the safety-arm 65, is a coil-spring 68 which, when assembled thusly on the pivot-pin, is under slight compression, as a consequence of which the entire safety assembly, including the pivot-pin 51, operating-handle 63 and safety-arm 65, is urged to the right, thereby taking up any slack between the respective members of the safety assembly and holding a knob 69 of the operating-handle in firm frictional engagement with the adjacent wall of the receiver whereby the safety-arm 65 is successfully held in its "on" and "off" positions.

The safety-arm 65 is adapted to project up through the longitudinal slot 53 of the transmitting-member and to be moved into and out of engagement with the underside of the sear 30 rearwardly of its pivot-pin for locking and unlocking the latter, the forward and rearward movements of the safety-arm corresponding to its "on" and "off" positions, being limited by engagement with the front and rear ends respectively of the slot 53.

Referring now to Fig. 8, the disconnector 45 comprises a relatively-thin flat strip of metal having a pivot-post 70 fastened to the underside thereof intermediate its opposite ends. The forward end of the disconnector is provided with a cam-lug 71 which comprises, in the preferred embodiment, a lip or flange 72 which is bent up-

wardly from a rearwardly-extending bevel formed at the forward end of the disconnector and substantially perpendicular to the top surface thereof, and appendage 73 being bent inwardly across the left-hand edge of the disconnector. The front face of the upturned lip 72 forms a substantially-flat rearwardly-extending cam-surface 74. It will be understood, of course, that the cam-lug may be formed separately and welded or otherwise secured to the top of the disconnector, but the flange and appendage construction described above is by far the most economical construction.

The rearwardly-extending reach of the disconnector is resilient and provided with a step comprising a depending-riser 75 and a tread 76 extending rearwardly therefrom and in a plane substantially parallel to the top surface of the disconnector. Formed on the underside of the tread is a depending block-like member 77 which is preferably constructed by curling under an extension of the rear end of the tread to form a hollow substantially-rectangular-shaped connector-block. It will be understood, however, that the latter may constitute a separate solid member suitably fastened to the underside of the tread. In accordance with an additional purpose of this invention, the underside of the connector-block is provided with a substantially-flat beveled face 78, the transverse axis of which makes an angle of substantially 3° to the vertical which corresponds to the slope of the flat beveled surface 56 of the lifting-lug 55.

The disconnector is adapted to be supported within the receiver of the firearm between the sear 30 and the transmitting-member 44 with the cam-lug 71 at the forward end of the disconnector extending beneath the breech-bolt 17. The operation of the disconnector for selectively connecting and disconnecting the transmitting-member 44 to the sear 30 is effected by the breech-bolt in accordance with its position in the chamber of the receiver. To this end, the bottom of the breech-bolt (see Fig. 7) is formed with a narrow substantially straight cam-groove 79 which extends longitudinally thereof in the vertical plane of its longitudinal axis, the width of the cam-groove 79 being only slightly greater than the transverse dimension of the cam-lug 71. The rear end of the cam-groove 79 is provided on its left-hand side, as seen in Figs. 2 and 3, with a beveled inner edge 80 which extends outwardly and rearwardly at an angle corresponding to that of the cam-surface 74 of the disconnector and is adapted to be cooperatively engaged thereby, in the manner and for the purpose hereinafter described. The support for the disconnector 45 comprises the aforesaid pivot-post 70 which projects down through a bushing 81 secured in the bottom of the receiver, the bushing being provided at its upper end with a flanged head 82 on which the disconnector is supported at a predetermined elevation within the receiver such that its cam-lug 71 will ride in the cam-groove 79 in the underside of the breech-bolt and the tread 76 at the rear end of the disconnector will engage the underside of the sear 30 forwardly of its pivot-pin. The disconnector is thus interposed between the sear and the transmitting-member with the connector-block 77 of the disconnector lying in a horizontal plane above the plane of the lifting-lug 55 of the transmitting-member. It will be clear that the vertical pivot-post 70 supports the disconnector for oscillation in a horizontal plane 75 within the receiver and that its rotation counter-

clockwise such as to bring the connector-block 77 into its right-hand position, as shown in Fig. 4 and hereinafter referred to as its normal position, is limited by engagement of the cam-face 74 of the lug 71 with the beveled edge 80 of the cam-groove 79. In its normal position, the connector-block 77 of the disconnector is immediately above the lifting-lug 55 of the transmitting-member. Hence, when the latter is elevated, its lug 55 will engage the connector-block 77 and flex the resilient rearwardly-extending reach of the disconnector upwardly. At the other extreme of its movement, hereinafter referred to as its disconnecting position, the connector-block 77 of the disconnector is displaced to the left of the lifting-lug 55 of the transmitting-member (see Fig. 5) to a position substantially opposite its slot 54, as a consequence of which the lifting-lug 55 will not make contact with the connector-block 77 when the transmitting-member is elevated by retraction of the trigger. The disconnector 45 is adapted to be resiliently held in its normal position by the force of yieldable means comprising a wire-spring 83 which, as shown most clearly in Figs. 2 and 3, comprises a substantially-Z-shaped mid-section provided with a forwardly-extending reach 84 held in juxtaposition to the right-hand inside wall of the trigger-plate by a right-angle bent adapted to engage in an aperture thereof. A relatively-short reach 85 extends rearwardly from the Z-shaped mid-section of the spring and is engaged at its rear end in a diametrical aperture in the lower end of the pivot-post 70. Normally, the rearwardly-extending reach 85 of the spring acts to resiliently hold the disconnector in its normal right-hand position, as shown in Fig. 2, but whenever the disconnector is swung horizontally clockwise from its normal position to its disconnecting position, as shown in Fig. 3, the spring will be distorted and, hence, on removal of the force which has displaced the disconnector from its normal position to its disconnecting position, the force of the distorted spring will swing the disconnector counterclockwise back to its normal position.

The operation of the anti-doubling means may be described briefly as follows. Assuming that the breech-bolt 17 is in battery, that is to say, is in breech-closing position, as shown in Figs. 1 and 2, then the beveled edge 80 of the cam-groove of the breech-bolt is forwardly of the cam-face 74 of the cam-lug 71 of the disconnector but substantially in contact therewith. Under these circumstances, the disconnector is resiliently held by its spring 83 in its normal position wherein its connector-block 77 is immediately above the lifting-lug 55 of the transmitting-member. Assuming further that the safety is in its "off" position, as indicated in Fig. 1, then on retracting the finger-piece 14 of the trigger for discharging the firearm, the bridge-member 42 of the trigger-arms 39 will be elevated, lifting the rear end of the transmitting-member so as to move the lifting-lug 55 thereof up against the underside of the connector-block 77 of the disconnector. The consequent upward force exerted against the connector-block flexes the resilient rearwardly-extending reach of the disconnector upwardly in a vertical plane, whereupon the tread 76 of the disconnector elevates the forward end of the spring-biased sear 30 to withdraw its nose 33 out of engagement with the shoulder 34 of the firing-plunger 28. The firing-plunger is thus released and thrust forwardly forcefully by the force of its compressed spring 29 to strike the firing-pin 24

and discharge the cartridge in the chamber of the barrel. Following the discharge of the cartridge and the subsequent rearward movement of the breech-bolt 17 in the chamber of the receiver for reloading and rearming the fire arm, the beveled edge 80 of the breech-bolt cam-groove moves rearwardly relative to the cam-face 74 of the cam-lug 71 and in so doing displaces the latter inwardly into alignment with the cam-groove 79, the disconnector being swung clockwise, as seen in Fig. 2, against the resistance set up by distorting the spring 83, whereupon the cam-lug 71 enters the longitudinal cam-groove 79 of the breech-bolt, as shown in Fig. 3. As a consequence of this movement, the rear end of the disconnector, and more especially its connector-block 77, will be displaced to the left of the lifting-lug 55 of the transmitting-member thereby disconnecting the transmitting-member and the disconnector. Moreover, the latter will be held in its disconnecting position throughout substantially the entire rearward and forward excursion of the breech-bolt and until the latter has again returned to battery. It will be manifest, therefore, that as long as the breech-bolt is out of breech-closing position, a rearward pull on the finger-piece 14 of the trigger would be ineffective for letting off the sear. Thus, the firearm will automatically rearm and will remain cocked until the breech-bolt has returned to battery and the trigger again pulled to fire a second shot. Moreover, even though the trigger were held retracted following the discharge of the firearm and the subsequent return of the breech-bolt to battery, the upward displacement of the lifting-lug 55 of the transmitting-member would effectively prevent the connecting-block 77 of the disconnector from moving back to its normal position above the lifting-lug of the transmitting-member until such time as the latter had been lowered by releasing the trigger. That is to say, there must be a conscious release of the trigger following each discharge of the firearm before a second shot may be fired. On return of the breech-bolt into battery, the beveled edge 80 of the cam-groove 79 will again be located forwardly of and substantially in contact with the cam-face 74, as a consequence of which the stressed wire-spring 83 of the disconnector will return the latter to its normal position for re-engagement with the transmitting-member.

It should be pointed out that engagement of the lifting-lug 55 of the transmitting-member with the connector-block 77 of the disconnector is effected by mutual engagement of the respective flat beveled surfaces 56 and 78 thereof, each of which is formed at an angle of substantially 3° to the vertical. This construction is preferred for facilitating disengagement and re-engagement of these respective surfaces and more especially for taking up wear therebetween so as to constantly hold a close tolerance. Mutual engagement between the cam-surface 74 and the beveled edge 80 of the cam-groove 79 causes these surfaces to wear and since the force of the spring 83 is acting on the disconnector to rotate the latter in a counterclockwise direction as seen in Fig. 2, the connector-block will move to the right relative to the lifting-lug 55, as seen in Fig. 4, whereby the beveled surface 56 of the latter will engage further up on the beveled surface 78 of the connector-block thereby automatically compensating for wear and holding a close tolerance between the beveled surfaces of the lifting-lug 55 and of the connector-block.

The improved anti-doubling device of this invention provides a durable, extremely simple and relatively inexpensive mechanism which occupies a minimum of space in the firearm and which is positive in its action, these and other advantages and improvements of the device being obtained through the expeditious use of materials and design whereby each element of the device performs several functions.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. In a self-loading firearm a receiver; a breech-bolt reciprocable in said receiver; firing-means mounted in said breech-bolt; a spring-biased sear adapted normally to coact with said firing-means to hold said firing-means in cocked position; a trigger; and anti-doubling means interposed between said trigger and said sear and arranged normally, that is to say, only when said breech-bolt is in battery to actuate said sear and release said cocked firing-means in response to retraction of said trigger, said anti-doubling means comprising a transmitting-member, an element arranged to support said transmitting-member for displacement vertically by retraction of said trigger, a disconnector, an element arranged substantially perpendicularly to the supporting-element of said transmitting-member to support said disconnector between said transmitting-member and said sear for displacement horizontally to and from operative relationship with said transmitting-member and said sear, and an element carried by said disconnector and yieldable substantially vertically with respect thereto for engagement with said transmitting-member and said sear thereby to actuate said sear and release said cocked firing-means in response to displacement of said transmitting-member by said trigger.

2. In a self-loading firearm a receiver; a breech-bolt reciprocable in said receiver; firing-means mounted in said breech-bolt; a spring-biased sear adapted normally to coact with said firing-means to hold said firing-means in cocked position; a trigger; and anti-doubling means interposed between said trigger and said sear and arranged normally, that is to say, only when said breech-bolt is in battery to actuate said sear and release said cocked firing-means in response to retraction of said trigger, said anti-doubling means comprising a transmitting-member, an element arranged to support said transmitting-member for displacement vertically by retraction of said trigger, a yieldable-element interposed between said transmitting-member and said receiver to hold said transmitting-member in contact with said trigger and normally to hold said trigger in its unretracted position, a disconnector, an element arranged to support said disconnector between said transmitting-member and said sear for displacement horizontally to and from operative relationship with said transmitting-member and said sear, and a yieldable-element arranged normally to hold said disconnector in operative relationship with said transmitting-member and said sear thereby to actuate said sear and release said

cocked firing-means in response to displacement of said transmitting-member by said trigger.

3. In a self-loading firearm a receiver; a breech-bolt reciprocable in said receiver; firing-means mounted in said breech-bolt; a spring-biased sear adapted normally to coact with said firing-means to hold said firing-means in cocked position; a trigger; anti-doubling means interposed between said trigger and said sear for actuating said sear so as to release said cocked firing-means in response to retraction of said trigger comprising a transmitting-member, an element arranged to support said transmitting-member for displacement vertically by retraction of said trigger, a disconnector, a cam-lug carried by said disconnector, an element arranged substantially perpendicularly to the supporting-element of said transmitting-member to support said disconnector between said transmitting-member and said sear for displacement horizontally to and from operative relationship with said transmitting-member and said sear, a connector-element carried by said disconnector and yieldable substantially vertically with respect thereto, and a yieldable-member arranged normally to hold the said connector-element of said disconnector in operative relationship with said transmitting-member and said sear thereby to actuate said sear and release said cocked firing-means in response to displacement of said transmitting-member by said trigger; and a cam-groove in said breech-bolt arranged to coact with the cam-lug of said disconnector when said breech-bolt is out of battery to move the said connector-element of said disconnector out of operative relationship with said transmitting-member against the resistance of said yieldable-element so as to prevent the release of said cocked firing-means in response to displacement of said transmitting-member by said trigger.

4. In a self-loading firearm a receiver; a breech-bolt reciprocable in said receiver; firing-means mounted in said breech-bolt; a spring-biased sear adapted normally to coact with said firing-means to hold said firing-means in cocked position; a trigger; and anti-doubling means interposed between said trigger and said sear and arranged normally, that is to say, only when said breech-bolt is in battery to actuate said sear and release said cocked firing-means in response to retraction of said trigger, said anti-doubling means comprising a transmitting-member arranged to be displaced upwardly substantially vertically by retraction of said trigger and a disconnector arranged to be supported between said transmitting-member and said sear for pivotal movement in a horizontal plane said disconnector having a resilient arm located normally immediately above said transmitting-member whereby as the latter is displaced upwardly by said trigger said transmitting-member engages and flexes said resilient arm upwardly into contact with said sear to actuate said sear and release said cocked firing-means.

5. In a self-loading firearm a receiver; a breech-bolt reciprocably mounted in said receiver; firing-means mounted in said breech-bolt; a spring-biased sear adapted normally to coact with said firing-means to hold said firing-means in cocked position; a trigger; and anti-doubling means interposed between said trigger and said sear and arranged normally, that is to say, only when said breech-bolt is in battery to actuate said sear and release said cocked firing-means in response to retraction of said trigger,

said anti-doubling means comprising a transmitting-member pivotally supported at its forward end in said receiver for substantially-vertical movement, the rear end of said transmitting-member being supported on said trigger and elevated thereby when said trigger is retracted, and a disconnector supported intermediate its opposite ends in said receiver on an axis substantially perpendicular to the pivotal supporting means of said transmitting-member for substantially-horizontal movement between said transmitting-member and said sear said disconnector having a resilient arm provided with a connector-element arranged normally to overlie said transmitting-member whereby as the latter is displaced upwardly by said trigger said transmitting-member engages and flexes the arm of said disconnector upwardly thereby to move said connector-element into contact with said sear to actuate said sear and release said cocked firing-means.

6. In a self-loading firearm a receiver; a breech-bolt reciprocably mounted in said receiver; firing-means mounted in said breech-bolt; a spring-biased sear adapted normally to coact with said firing-means to hold said firing-means in cocked position; a trigger; anti-doubling means interposed between said trigger and said sear for actuating said sear so as to release said cocked firing-means in response to retraction of said trigger comprising a transmitting-member pivotally supported at its forward end in said receiver for substantially-vertical movement, resilient means carried by said transmitting-member arranged to coact with said receiver to hold the rear end of said transmitting-member in engagement with said trigger thereby to hold said trigger normally in its unretracted position, and a resilient disconnector supported intermediate its opposite ends in said receiver for substantially-horizontal movement between said transmitting-member and said sear said resilient disconnector being arranged normally to overlie said transmitting-member whereby as the latter is displaced upwardly by said trigger said transmitting-member engages and flexes said resilient disconnector upwardly into contact with said sear to actuate said sear and release said cocked firing-means; and means carried by said breech-bolt arranged to coact with said flexible disconnector when said breech-bolt is out of battery to displace said disconnector out of alignment vertically with said transmitting-member so as to prevent the actuation of said sear and release of said cocked firing-means in response to the elevation of said transmitting-member by said trigger.

7. In a self-loading firearm a receiver; a breech-bolt reciprocably mounted in said receiver; firing-means mounted in said breech-bolt; a spring-biased sear adapted normally to coact with said firing-means to hold said firing-means in cocked position; a trigger having a transverse bridge-element; anti-doubling means interposed between said trigger and said sear for actuating said sear so as to release said cocked firing-means in response to retraction of said trigger comprising a transmitting-member having an upwardly-projecting lug intermediate its opposite ends, a transverse pivot engaged in the forward end of said transmitting-member and arranged to pivotally support the latter for substantially-vertical movement in said receiver, and resilient means carried by said pivoted transmitting-member arranged to hold the rear end

thereof down in contact with said trigger bridge-element thereby to hold said trigger normally in its non-retracted position, a resilient disconnector interposed between said transmitting-member and said sear, said disconnector having a vertical pivot-post intermediate its opposite ends arranged to pivotally support said disconnector for substantially-horizontal movement in said receiver, a depending-block at the rear end of said disconnector, a cam-lug at the forward end of said disconnector, and a spring connected to said vertical pivot-post to bias said disconnector in a horizontal position such that said depending-block is normally immediately above the upwardly-projecting lug of said transmitting-member, said trigger bridge-element being arranged to engage the rear end of said transmitting-member and elevate its upwardly-projecting lug into engagement with said depending-block on retraction of said trigger to flex said resilient disconnector upwardly thereby to actuate said sear and release said cocked firing-means; and a cam-groove in the underside of said breech-bolt arranged to coact with the cam-lug of said disconnector when said breech-bolt is out of battery to displace the depending-block of said disconnector out of alignment vertically with the upwardly-projecting lug of said transmitting-member so as to prevent the actuation of said sear and release of said cocked firing-means in response to the elevation of the rear end of said transmitting-member on retraction of said trigger.

8. In a self-loading firearm a receiver; a breech-bolt reciprocably mounted in said receiver; firing-means mounted in said breech-bolt; a spring-biased sear adapted normally to coact with said firing-means to hold said firing-means in cocked position; a trigger having a transverse bridge-element; anti-doubling means interposed between said trigger and said sear for actuating said sear so as to release said cocked firing-means in response to retraction of said trigger comprising a transmitting-member having an upwardly-projecting lug intermediate its opposite ends and provided with a vertically-beveled top surface, a transverse pivot engaged in the forward end of said transmitting-member and arranged to pivotally support the latter for substantially-vertical movement in said receiver, and resilient-means carried by said pivoted transmitting-member arranged to hold the rear end thereof down in contact with said trigger bridge-element thereby to hold said trigger normally in its non-retracted position, a resilient disconnector interposed between said transmitting-member and said sear said disconnector having a vertical pivot-post intermediate its opposite ends arranged to pivotally support said disconnector for substantially-horizontal movement in said receiver, a depending-block at the rear end of said disconnector having a vertically-beveled bottom surface, a cam-lug at the forward end of said disconnector, and a spring connected to said vertical pivot-post to bias said disconnector in a horizontal position such that said depending-lug is normally immediately above the upwardly-projecting lug of said transmitting-member, said trigger bridge-element being arranged to engage the rear end of said transmitting-member and elevate the vertically-beveled top surface of its upwardly-projecting lug into engagement with the vertically-beveled bottom surface of said depending-block to flex said resilient disconnector upwardly thereby to

actuate said sear and release said cocked firing-means; and a cam-groove in the underside of said breech-bolt arranged to coact with the cam-lug of said disconnector when said breech-bolt is out of battery to displace the depending-lug of said disconnector out of alignment vertically with the upwardly-projecting lug of said transmitting-member so as to prevent the actuation of said sear and release of said cocked firing-means in response to the elevation of the rear end of said transmitting-member on retraction of said trigger.

9. In a self-loading firearm a receiver; a breech-bolt reciprocably mounted in said receiver; firing-means mounted in said breech-bolt; a spring-biased sear adapted normally to coact with said firing-means to hold said firing-means in cocked position; a trigger; a safety comprising an arm constructed and arranged to be manually moved into engagement with said sear to prevent disengagement thereof from said cocked firing-means; and anti-doubling means interposed between said trigger and said sear for actuating said sear so as to release said cocked firing-means in response to retraction of said trigger comprising a transmitting-member having a slot to accommodate the arm of said safety, the opposite ends of said slot constituting abutments to limit the forward and rearward move-

ments of said safety, said transmitting-member being pivotally supported at its forward end in said receiver for substantially-vertical movement therein, and a resilient element arranged to hold the rear end of said transmitting-member in engagement with said trigger so as to be elevated thereby when said trigger is retracted, and a resilient disconnector pivotally supported intermediate its opposite ends in said receiver between said transmitting-member and said sear for substantially-horizontal movement therebetween, said resilient disconnector being arranged normally to overlie said transmitting-member and to be engaged and deflected upwardly thereby when said trigger is retracted thereby to engage and actuate said sear and release said cocked firing-means.
